UNITED STATES PATENT OFFICE.

GLENN B. WARREN, OF SCHENECTADY, NEW YORK, ASSIGNOR TO GENERAL ELECTRIC COMPANY, A CORPORATION OF NEW YORK.

ELASTIC-FLUID TURBINE.

Application filed June 24, 1924. Serial No. 722,120.

The present invention relates to elastic fluid turbines and especially to diaphragm packings for turbines of the type wherein the casing or housing is divided into stages by nozzle diaphragms, although as to certain broader aspects, it is not necessarily limited thereto.

In connection with the operation of elastic fluid turbines, it is known that when a turbine is operating at full load, it runs more smoothly and is less likely to vibrate than when running at light load. This is because a turbine when running at full load is evenly heated and is subjected to little if any temperature and pressure changes. On the other hand, when a turbine is running at light load or is being started up, it may be subjected to changes in temperature and pressure of considerable magnitude and at such times is much more likely to operate unevenly or to vibrate.

Now, in the operation of elastic fluid turbines, it is desirable that the packings run with as close a clearance as it is possible to maintain so as to reduce the leakage to a minimum and it follows from the foregoing that because of the greater smoothness of operation, closer packing clearance can be maintained when the turbine is operating at full load than when it is being started up or is operating at lighter loads, and the object of my present invention is to provide an improved packing which is automatically adjusted so as to vary the clearance in accordance with the load on the turbine, the clearance being the closest when the turbine is operating under full load conditions.

For a consideration of what I believe to be novel and my invention, attention is directed to the accompanying description and the claims appended thereto.

In the drawing, Fig. 1 is a sectional view of a part of an elastic fluid turbine having a diaphragm packing embodying my invention; Figs. 2 and 3 are detail views on a larger scale, illustrating the operation of my invention; and Fig. 4 is a detail view of a modification.

Referring to the drawing, 5 indicates the casing of an elastic fluid turbine, which casing is divided into stages by nozzle diaphragms 6, the nozzles being indicated at 7. Nozzles 7 receive elastic fluid from buckets

8 on a wheel 9 of a preceding stage and discharge it to buckets 10 on a wheel 11 in the following stage, wheels 9 and 11 being carried by a shaft 12. Only one diaphragm and the adjacent turbine wheels are shown in the drawing, the illustration of only a portion of a turbine being necessary to an understanding of my invention.

The construction so far described is a known one and is to be taken as typical of any turbine structure to which my invention may be applied.

Now, according to my invention as carried out in connection with diaphragm packing, I provide on the shaft a packing element 13 comprising annular packing teeth 14 and on the diaphragm a packing element 15 comprising annular packing teeth 16 which cooperate with packing teeth 14. When a turbine is in operation, there is a drop in pressure across the diaphragms which drop in pressure increases with the load and this pressure on the diaphragm causes them to deflect somewhat toward the low pressure end of the machine, the deflections being the greatest when the turbine is operating at full load. In carrying out my invention, I take advantage of this fact and utilize the deflection of the diaphragms due to increase in the load for varying the clearance of the packings. To this end, I arrange the packings so that when the diaphragm deflects toward the low pressure end of the turbine, the clearance in the packing will be decreased and I then so construct the packing that there is ample clearance at no load and so that the desired closer clearance will be established at full load due to the deflection of the diaphragm.

Referring to Figs. 1, 2 and 3, it will be seen that the desired result is obtained by tapering the packing elements, the packing elements on both the diaphragm and the rotor being tapered or having conical packing surfaces in the present instance, and it will be clear that with this arrangement when the diaphragm deflects toward the low pressure end of the machine, i. e., toward the right in the drawing, the clearance in the packing will be decreased. This is well illustrated in the enlarged views in Figs. 2 and 3 wherein Fig. 2 illustrates the normal no load position of the packing ele-

ments, and Fig. 3 illustrates the position of the packing elements when the diaphragm is deflected under full load conditions of operation.

5 The specific type of packing elements comprising the straight teeth 14 cooperating with the sloping teeth 16 are shown only by way of example and as being a desirable form of packing structure to use in 10 carrying out my invention. They form no part of my present invention. Any suitable type of packing may be used.

In Figs. 1 to 3, the straight teeth are shown as being carried on the rotor and 15 the sloping teeth as being carried by the diaphragm. However, I may use the reverse of this arrangement and such a reverse arrangement is shown in Fig. 4 of the drawing wherein 17 indicates the dia- 20 phragm provided with the straight toothed packing element 18, and 19 indicates the rotor or shaft provided with the sloping toothed packing element 20. In this arrangement, the extent of the contact be- 25 tween packing element 20 and shaft 19 is decreased by providing a groove 21 in the bore element 20. This serves to prevent rapid transfer of heat from the packing element 20 to the shaft, a thing which, as 30 is known, it is desirable to avoid.

In accordance with the provisions of the patent statutes, I have described the prin-

ple of operation of my invention, together with apparatus which I now consider to represent the best embodiments thereof, but I 35 desire to have it understood that the apparatus shown is only illustrative and that the invention may be carried out by other means.

What I claim as new and desire to se- 40 cure by Letters Patent of the United States, is:

The combination with an axial flow multi-stage elastic fluid turbine, of means for varying an interstage packing clearance there- 45 in in response to load on the turbine, said means comprising a diaphragm between two stages, which diaphragm is sufficiently flexible to deflect toward the low pressure end of the turbine increasingly as the pressure drop across it increases, a packing element 50 carried by the diaphragm and arranged to move therewith axially when the latter is deflected, and a packing element with which said first-named packing element cooperates 55 to provide the interstage packing clearance, said packing elements being annular in form, concentric, and tapered in the direction of the high pressure end of the turbine whereby the clearance between them is an- 60 nular and tapers in the same direction.

In witness whereof, I have hereunto set my hand this 23rd day of June, 1924.

GLENN B. WARREN.
